UNITED STATES PATENT OFFICE.

CHARLES L. DEPOLIER, OF NEW YORK, AND EDWARD C. DUNCUFF, OF MOUNT VERNON, NEW YORK, ASSIGNEES TO DUBCIS WATCH CASE COMPANY, OF BROOKLYN, NEW YORK, A CORPORATION OF NEW YORK.

EXPANSIBLE SECURING DEVICE FOR WATCH-BRACELETS.

1,151,927.

Specification of Letters Patent. Patented Aug. 31, 1915.

Application filed March 16, 1914. Serial No. 825,076.

To all whom it may concern:

Be it known that we, CHARLES L. DEPOLIER and EDWARD C. DUNCUFF, citizens of the United States, residing at New York city, county of Kings, State of New York, and Mount Vernon, in the county of Westchester and State of New York, respectively, have invented certain new and useful Improvements in Expansible Securing Devices for Watch-Bracelets, of which the following is a specification.

Our invention relates to novel means for securely fastening together the two ends of a chain or other article when it is desired to couple the ends together, and is especially designed for use in securing a watch, locket, or other suitable useful and ornamental article to the ends of an expansible bracelet.

The main object of this invention is to provide expansible fastening means secured at each end of a bracelet or intermediate the ends thereof, which may be manipulated with the greatest of facility whereby the range in the size of the bracelet may be varied beyond the limits of expansion, as permitted by the well known construction of expansible bracelet, in order to allow the bracelet to be passed over the hand and on to the wrist, and then caused to assume its normal size, while it is secured to a watch or other article.

A further object is to provide an expansible securing device for effecting variations in the size of bracelets with the greatest of facility, and means whereby the component parts may be assembled with security, and linked and uncoupled with the greatest of ease, as well as to promote neatness and simplicity in structure and finish.

The foregoing and such other objects as may occur from the ensuing description are attained by the construction, combination, arrangement and location of the parts hereinafter more fully described, illustrated in the accompanying drawings forming a part of this specification, and particularly pointed out in the claims appended hereto.

With reference to the drawings:—Figure 1, is a perspective view of an expansion bracelet showing a watch attached to each end thereof by the improved securing means embodying our invention. Fig. 2, is a side view showing a portion of a bracelet with

our improved securing means fastened to the links of the bracelet intermediate the ends thereof. Fig. 3, is a side view of the securing means showing the parts in their expanded position. Fig. 4, is a side view showing the parts in their contracted position. Fig. 5, is a side view showing the two parts detached and separated from each other. Fig. 6, is a perspective view showing the two parts in partly expanded position. Fig. 7, is a plan view of the two parts separated from each other. Fig. 8, is a side view showing one of the parts with the end piece separated therefrom. Fig. 9, is a side view showing one of the parts after the end piece has been placed thereon, and in its unfinished condition. Fig. 10, is a plan view of the part shown in Fig. 9, showing one end in its unfinished condition. Fig. 11, is an end view of the end portion of one of the parts separated therefrom, and Fig. 12, is a longitudinal sectional view through one of the parts showing the other part in section and side elevation, both parts being in partly expanded position.

Similar characters of reference indicate corresponding parts throughout the several figures of the drawings.

The numeral 1 indicates the links of an expansible bracelet, and 2 the watch to which the bracelet is attached at each end thereof by the securing means hereinafter described.

By reference to the drawings it will be readily perceived that our improved securing device consists of an expansible structure composed of two members or links slidably secured to each other, in order that they may be manipulated into an expanded or contracted position with great facility.

One of the members 3, consists of an open link separated at its upper and forward end portion at an incline to the direction of its length to form a hook portion 4, the rear end portion being provided at each side with an integral lateral projection 5, the upper portion thereof being resilient from its rear portion to the point of separation, and said upper portion being gradually inclined upwardly and forwardly to form a hump portion 6 for the purpose hereinafter described. The other member or link 7, is composed of two side pieces 8 which are merged together

at one end and terminate in a stationary hook portion 9, and at the other end are connected by a member 10, which is fixedly secured to said side pieces in any suitable or desirable manner. Each side piece 8 is provided with a longitudinal groove in its inner surface extending substantially throughout its length, having an abutment at its outer end, and adapted to receive the projections 5, thus serving to retain the member 3 in position between said side pieces and acting as a guide when the parts are given a reciprocal movement back and forth and into the expanded and contracted position.

15 It will be seen that the end member 10 is provided with grooves 11 at both its upper and lower portion, said grooves being in alinement with the opening 12 formed in the end member 10, in order that inner link 20 member 3 may slide freely through the grooves in said end member and when the two members 3 and 7 are caused to assume the closed or contracted position, the shouldered portion 13 of the resilient or hump 25 portion of member 3 will spring upward and rest behind the end portion 10 of member 7, the said member or portion 10 serving to cover and close the separated portions of member 3, thus locking the hook portion 30 and preventing the disengagement of any article secured thereto.

In Fig. 8 the end member 10 is shown before being placed on the side pieces 8, but it will be understood that it is carefully placed on said side pieces so that the grooves 35 11 (Fig. 11) will be in alinement with the opening 12 between said side pieces as shown in Fig. 10, after which the end member 10 is subjected to the filing and finishing operation to make it assume the shape shown in 40 Figs. 2 and 3.

It will be understood that our securing means is provided with a hook at each end portion thereof for securing an article thereto, and when the parts are in the expanded or partly expanded position any suitable article may be readily attached to or detached from the hook end portion of member 3 by depressing the upper resilient portion, which 45 50 portion will immediately spring back and close the hook end portion when pressure on the resilient portion is relieved. The stationary hook will now be open for the purpose of attaching any suitable article thereto. When the parts are caused to assume the closed or contracted position the end portion 10 of member 7 closes the hook end portion of member 3, while the rear 55 60 end portion of said member 3 closes the opening to the stationary hook 9, the member 3 being locked in position by the humps being resiliently held against the part 10.

By the attachment of our improved expandable securing means to each end of an expandable bracelet it will be seen when in the

expanded position to furnish the desired increase in the size of the bracelet to facilitate its being easily passed over the hand in adjusting the bracelet on the wrist and by closing the parts to take up the increase 70 in size so as to hold the watch snugly on the wrist of the wearer.

This invention constitutes an improvement on the securing device set forth in an application filed by us under date of February 75 10, 1914, bearing Serial No. 817,745.

It will be obvious that slight changes may be resorted to in the precise details of construction herein set forth without departing from the spirit of our invention.

Having thus described our invention what we claim and desire to secure by Letters Patent is:—

1. Means for securing a watch to an expandable bracelet at each end thereof, comprising an expandable link structure composed of two members slidably connected to each other, each member having a hook at one end thereof, means forming a part of each of said members for locking the members together when closed, and the inner portion of each member being adapted to close the hook of the other member when the parts are contracted.

2. A device for securing the two ends of an article, consisting of an expandable structure composed of two interlinked members slidable in relation to each other, one member being an open link provided with a hook at one end and having a resilient upper portion for opening and closing said hook, the other member consisting of two side pieces terminating in a hook at one end, means forming a portion of each member for locking the members together when closed and the inner portion of each member being adapted to close the hook of the other member when the parts are contracted.

3. A device for securing the two ends of an article, consisting of an expandable structure composed of two interlinked members, each member having a hook at its free end, one member being an open link having a resilient portion for opening and closing the hook thereof, the other member comprising two side pieces connected together at each end thereof, means for slidably connecting the two members, means forming a part of each of said members for locking the members together when closed and the inner portion of each member being adapted to close the hook of the other member when the parts are contracted.

4. A device for securing the two ends of an article, consisting of an expandable structure composed of two interlinked members, one member consisting of two side pieces connected and provided with a hook at one end and connected at the other end by a piece provided with longitudinal grooves

adapted to receive the other member, and
said other member being composed of an
open link having a hook at one end and a
resilient upper portion for opening and clos-
ing the hook thereof, means for slidably
connecting the two members, means forming
a portion of each member for locking
the members together when closed and the
inner portion of each member being adapted

to close the hook of the other member when 13
the parts are contracted.

In testimony whereof we affix our signa-
tures in presence of two witnesses.
